INSERT FOR FIELD CAPS

Elizabeth R. Stone, Woodhaven, N. Y.

Application June 19, 1952, Serial No. 294,375

1 Claim. (Cl. 2—199)

This invention relates to an insert for maintaining a cap and the like in correct formation.

The invention primarily comprehends an insert for an officer's field cap and the like which snugly fits continuously about the inside of the upstanding wall thereof so as to provide a support therefor and maintain the crown in regulation formation.

Still another object of the invention is to provide an insert of said character which is fashioned from a length of sheet material and which is adapted to be adjustably secured together in band formation for varying the size of the band so that the same may snugly fit against the upstanding wall of the cap.

Still another object of the invention is to provide an insert which is adjustable whereby the same may be made larger or smaller to fit different sizes of hats.

With the foregoing and other objects in view, reference is now made to the following specification and accompanying drawings in which the preferred embodiment of the invention is illustrated.

In the drawings:

Fig. 1 is a perspective view of a field cap provided with an insert constructed in accordance with the invention.

Fig. 2 is a horizontal sectional view taken approximately on line 2—2 of Fig. 1.

Fig. 3 is a vertical sectional view taken approximately on line 3—3 of Fig. 2.

Fig. 4 is a vertical sectional view taken approximately on line 4—4 of Fig. 3.

Fig. 5 is a view in elevation of the insert in plane formation before securing the same in band formation.

Referring to the drawings by characters of reference, the invention is illustrated in its application to a cap 10 such as an officer's field cap which is formed with an upstanding peripheral wall 11, a plane forwardly sloping top wall 12 and a peak 13. A flap 14 is secured to the bottom edge of the peripheral wall 11 which extends about the sides and the rear thereof for use in cold weather for covering the ears and which is adapted to be inturned in parallel relation with the peripheral wall 11 when not in use.

The cap 10 is provided with an insert 16 which corresponds to the shape and formation of the upstanding peripheral wall 11 so as to engage against the inside face thereof to support the said wall in upstanding stiffened relation and to retain the top of the cap against sagging and the top wall 12 in forwardly sloping formation. The insert 16 is fashioned from stiff sheet material to provide an elongated strip which is formed with rectangular shaped end portions 17 and 18 of substantially the same width

2

and intermediate the said end portions the upper and lower edges 19 and 20 of the strip converge inwardly to the medial portion 21 forming the narrowest portion of the strip.

5 In order to secure the insert in band formation so as to render it adjustable for accommodating different sizes of hats and for adjustably securing the same snugly against the inner face of the upstanding peripheral wall 11, the ends 17 and 18 of the strip are provided with interengagable fastening means for securing the same together in overlapped relation to permit relative adjustment of the ends. As illustrated, the end 17 of the strip is formed with an elongated slot 23 located substantially medially between the upper and lower edges thereof and adapted to slidably engage in said slot is a threaded stud 24 affixed to the end 18 of the strip in longitudinal alignment with the slot 23. When disposed in adjusted relation in the slot to provide the desired size of band, the stud 24 is adapted to be secured in fixed position by tightening of the 10 nut 25 thereon. This disposed the ends 17 and 18 in overlapped relation and when so arranged a threaded stud 26 provided in the end 17 is inserted through an opening in the end 18 which may be punched as desired or a plurality of openings 27 may be provided for selectively receiving 15 the stud 26 which is secured therein by tightening of the nut 29.

While the preferred form of the invention has been illustrated and described herein, it is to be understood that the same is not so limited and the invention will cover 20 and include any and all forms which fall within the purview thereof.

What is claimed is:

A stiffening band adapted to be arranged within a cap against the peripheral side wall thereof for stiffening the 25 same consisting of an elongated strip of stiff material having end portions formed with parallel upper and lower edges and an intermediate portion tapering along the upper and lower edges toward the middle of the strip, one of said end portions having an elongated slot and the other 30 end portion having a stud slidably in said slot with the end portions disposed in overlapping relation, said end portions being relatively adjustable to dispose said stud at any desired position in said slot for varying the size of the band, one of said end portions having a stud adjacent 35 one of the longitudinal edges thereof and the other of said end portions having a plurality of longitudinally spaced openings adapted to be selectively engaged by said last 40 mentioned stud for securing the overlapped end portions in fixed adjusted position so as to expand the side 45 wall of the cap, and said studs having heads adapted to 50 be removed for disconnecting the end portions of the band to permit of the removal of the band from the cap for use of the cap independently of the band.
